PACKAGING MACHINE AND METHOD OF
PACKAGING

Michael J. Milmoe, Glen Ellyn, and Clarence J. Malhiot, Oak Park, Ill., assignors to F. B. Redington Co., Chicago, Ill., a corporation of Illinois

Application September 17, 1937, Serial No. 164,364

21 Claims. (Cl. 226—14)

This invention relates to a packaging machine and the method of packaging and more particularly to an automatic machine for feeding and packaging articles.

5 An important object of the invention is the provision of a new and novel packaging machine which is provided with means for arranging a slip or circular in the bottom of a container; which is provided with means for arranging a predetermined number of articles or tablets into the container on top of the slip or circular; which is provided with means for placing a slip, card or the like containing printed matter such as directions pertaining to the use of the articles 10 or tablets; which is provided with means for folding an advertising circular and then placing it in the container on top of the last mentioned slip or on top of the articles and which is provided with improved means for closing the cover of the 15 container.

Another object of the invention is the provision of a new and improved method for packaging articles such as circular tablets by arranging a circular in a container having a hinged top, moving the container along predetermined paths whereby rows of such circular tablets are fed into the container, placing a slip, card or the like containing printed matter such as directions pertaining to the use of the articles or tablets, then 20 folding a circular and providing a predetermined number of folds therein, placing the circular in the container on top of the tablets and then finally closing the top of the container.

Other objects of the invention are the provision 25 of an automatic packaging machine including means for inserting a strip of paper into the bottom of the container as the container is being fed along a predetermined path; means for inserting a predetermined number of tablets into the container as it is being conveyed along a predetermined path and for positioning the tablets in a uniform manner in the container; means for placing a slip, card or the like containing printed matter such as directions pertaining to the use 30 of the articles or tablets; means for folding a circular as the container is conveyed along a predetermined path and then feeding the circular into the package in a predetermined manner; and means for maintaining the hinged cover of the 35 container in a predetermined position and then, after the packaging of the container has been completed, causing the top to be moved into closed position.

50 A still further object of the invention is to provide a plurality of elements and mechanism operating in a predetermined relationship in a synchronized manner so as to effect the complete operation of feeding, packaging and sealing.

55 Numerous other objects and advantages will be

apparent throughout the progress of the following specification.

The accompanying drawings illustrate a selected embodiment of the invention and the views therein are as follows:

Fig. 1 is an elevation of the improved machine;

Fig. 2 is a top plan view thereof;

Fig. 3 is a diagrammatic view of the escapement bars showing them in one of their operating positions;

Fig. 4 is a view similar to Fig. 3 but showing the escapement bars in another of their operating positions;

Fig. 5 is a detail sectional view of the escapement bars on the line 5—5 of Fig. 4;

Fig. 6 is a detail sectional view of an escapement bar on the line 6—6 of Fig. 5;

Fig. 7 is a detail sectional view on the line 7—7 of Fig. 2;

Fig. 8 is an elevational view of some of the 20 mechanism showing the presser arms mounted on the knife arm for pressing the first slip into the container;

Fig. 9 is a view similar to Fig. 8 showing the slip completely inserted within the container;

Fig. 10 is a top view of the container with the lid in open position and showing the slip in proper position in said container; (This view also illustrates the condition at Fig. 8.)

Fig. 11 is a detail elevational view of the article or tablet chute member;

Fig. 12 is a detail sectional view of the end of a chute member after a lateral row of tablets have been arranged in the container;

Fig. 12a is a detail sectional view showing the 35 operation of the pusher arm for moving the row of tablets placed in the container to one side of the container;

Fig. 13 is a view similar to Fig. 12 showing a second lateral row of tablets arranged in the container;

Fig. 13a is a view showing the position of the pusher arm after a second lateral row of tablets has been inserted in the container;

Fig. 13b is a view similar to Fig. 13a but showing the pusher arm having pushed the second row of tablets into their normal position;

Fig. 14 is a view similar to Figs. 12 and 13 but shows the three lateral rows of tablets positioned in the container;

Fig. 15 is an elevational view of the chute showing it in two positions;

Fig. 16 is an elevational view of the pusher bar showing the same in different positions;

Fig. 17 is a detail elevational view of some of the 55 mechanism showing the operation of the pusher bar and chute;

Fig. 18 is a view similar to Fig. 17 but showing the pusher bar in its rearward position;

Fig. 19 is a sectional view of some of the mech-

- anism for actuating the pusher arm to feed a slip from the hopper into the container;
- Fig. 20 is a plan view of some of the mechanism at the lower end of the hopper showing the tablet rotating bar and the tablet agitators at the start of the movement of the tablets;
- Fig. 21 is a view similar to Fig. 20 showing the agitators and the tablet rotating bar at approximately mid-stroke;
- Fig. 22 is a view similar to Figs. 20 and 21 but showing the position of the tablets at the fulfillment of the stroke of the tablet rotating bar and agitators;
- Fig. 23 is a detail sectional view on the line 15 23—23 of Fig. 2;
- Fig. 24 is a detail sectional view on the line 24—24 of Fig. 2;
- Fig. 25 is a detail sectional view on the line 25—25 of Fig. 2 showing a folded circular being 20 inserted in the container;
- Fig. 26 is a view similar to Fig. 25 showing the folded circular after insertion in the container;
- Fig. 27 is a top plan view of the mechanism shown in Fig. 25;
- Fig. 28 is a detail perspective view of the container in open position, showing tablets arranged 25 therein;
- Fig. 29 is a view similar to Fig. 28 showing a slip inserted on top of the arranged tablets;
- Fig. 30 is a view similar to Figs. 28 and 29 showing a folded circular arranged within the container;
- Fig. 31 is a detail sectional view of the container showing the lid locking means;
- Fig. 32 is a view taken on the line 32—32 of Fig. 37 showing part of the tablet agitators with tablets arranged in the channels;
- Fig. 33 is a view similar to Fig. 32 showing all 40 of the agitators and the support bars and the channels for the tablets;
- Fig. 34 is a detail plan view of some of the mechanism shown in Fig. 17 showing the bracket for carrying and operating the chute members;
- Fig. 35 is a view similar to Fig. 34 showing the connecting arm for the tablet pusher bars, certain parts being omitted for the sake of clearness;
- Fig. 36 is an elevational view of an individual tablet agitator showing the mounting thereof;
- Fig. 37 is an elevational view of the inclined conveyor or hopper and some of the actuating mechanism therefor;
- Fig. 38 is an elevational view of the bracket and tablet rails showing their connection to each other;
- Fig. 39 is a plan view of the structure shown in Fig. 38;
- Fig. 40 is a section taken transversely of the conveyor on the line 40—40 of Fig. 1 and showing the mechanism for causing the last roll of tablets to lie flat in the container; and
- Fig. 41 is a diagrammatic representation of the movement of the tablet-alining pusher bar of Figs. 17 and 18.
- The present invention is illustrated as applied to a machine for packaging disk shaped articles or tablets but the principle of operation of the disclosed machine is equally applicable to packaging of other articles.
- The invention relates in general to the packaging of a plurality of tablets in a container having a hinged top. The containers which receive the tablets are carried by a chain conveyor along a predetermined path, which conveyor is driven 75 intermittently or step by step and has a series of buckets or pockets for receiving the containers in open position. As soon as the containers arrive at a predetermined position, a piece of pre-cut material or paper is placed in the bottom of the container, the material being cut by a reciprocating knife, the movement of which is automatically synchronized with the feeding movement of the conveyor. The containers in the buckets continue along their path of movement until they arrive at a predetermined position under spaced chute members, which have received a plurality of tablets from a hopper, to feed an exact number of tablets into each container at a proper timed interval. Additional means are provided adjacent the tablet-feeding means for 10 positioning the tablets in the containers in a uniform manner. After the tablets are properly positioned and arranged in the container, the filled container is continued along a path of movement to a predetermined position where it receives a slip, card or the like containing printed matter, such as directions pertaining to the use of the tablets. The container of tablets is then moved to another predetermined position to receive a folded advertising circular in superposed 15 relation with the tablets. The circular is first folded to proper shape and then fed into proper position in the container. When the folding mechanism, which folds and feeds the advertising circular of folded dimensional size, is operated, 20 the container is moved by the conveyor to closing position where the hinged top will be closed to complete the packaging operation.
- Referring to the drawings and particularly to Figs. 1 and 2 thereof, the machine comprises a 25 frame 1 which is attached to a base or supporting member. Transverse shafts 2 are journaled in the frame 1 and carry sprocket wheels 3; only one of these shafts and sprockets being shown in Figs. 1 and 2. The sprocket wheels 3 support 30 and operate a conveyor belt 4 which comprises a plurality of individual conveying buckets, receptacles or plates 5 having a package or container receiving pocket. The buckets 5 are connected by links 10 secured to adjacent buckets 35 by pins 7 passing through the downwardly extending flanges or lugs 11. (See Figs. 7 and 19). The conveyor 4 and its auxiliary structure are supported and guided by stationary plates or bars 6 mounted on a bracket 8, the bracket 8 being bolted to the frame 1 by bolts 9.
- A small container 12, Figs. 10 and 28 to 31, is placed in each individual bucket 5 of the conveyor 4 and is fed along the path of the conveyor into the packaging machine. The conveyor buckets 5, carrying containers 12, are successively moved by the conveyor to a position designated as A (see Figs. 1 and 2), past a positioning pin 13 which is mounted at 14 to a bracket 15 attached to an extending arm 16 of an oscillating lever 17, Fig. 2. The pin 13 is vertically disposed, and has at its lower end a rubber tip 18, Fig. 1, for the purpose of adjusting the container 12 to its proper position in the conveyor bucket 5. The pin 13 carrying the rubber tip 18 is spring-urged by a helical spring 19, Fig. 1, which encircles the pin 13 intermediate the tip and the underside of the bracket 15.
- A web of thin paper is fed from a supply roll 20, Figs. 1 and 2, which is mounted on a shaft 21, the shaft 21 being attached to the frame in any convenient manner. The paper 22 from the roll 20 is fed about a tension roll 23, Figs. 2 and 7, which is mounted on a shaft 24. The shaft 24 is carried by arm 25 as shown in Fig. 7, and 75

the roll 23 allows the paper to be fed to feed rolls 26 and 27. The feed rolls 26 and 27 are mounted on shafts 28 and 29, respectively, which are supported by the frame 1 in any conventional manner, Figs. 2 and 7. The paper 22 is fed from the feed rolls between a guide member 30 and a fixed cutter 31, Fig. 7, into a position to be cut off by a reciprocating knife 32, which cooperates with the stationary knife 31. The knife 32 is actuated by the oscillating lever 17, the perpendicular extension or arm 16 of which has horizontal pins 33 to which the knife 32 is attached, Fig. 1. Also carried by this horizontally extending arm 16 is an angular bracket 34, Figs. 1, 2 and 7, which is bolted thereto by a bolt 35. The bracket 34 extends vertically downward to a position in front of the knife 32 and the paper 22 being fed, and acts as a presser arm or abutment for the front edge of the cut paper which is fed into the container 12.

The bracket 15, Figs. 1 and 2, carrying the positioning pin 13, is bolted in horizontal position on the lower side of the bracket 34 by a screw 36, Figs. 2 and 7. This bracket 15 extends along the direction of the feed of the conveyor, to the right, Figs. 1 and 2, to provide at the end opposite the positioning pin a pair of downwardly extending arms 37 and 38, Fig. 1, which act as presser arms or guides for pressing or directing the paper into the bottom of the container after the paper has been cut off by the knife, as shown in Figs. 8, 9 and 10. Upon movement of the conveyor the presser arms 37 and 38 which are immediately beyond the cutting position, prevent the cut-off paper from falling anywhere except immediately at the bottom of the container or carton. These arms also prevent the slip from riding or contacting one corner or side of the container, which condition might prevent proper insertion of the tablets into the containers.

The stationary knife 31 lies immediately adjacent the conveyor buckets 5 and cooperates with the reciprocating knife 32. Upon each oscillation of the lever 17 and its extension 16, the knife 32, in cooperation with the knife 31, cuts off a predetermined strip of paper 22 which falls into the open container 12 being conveyed by the buckets 5 into position thereto, and the strip is then pressed to the bottom of the container by the presser arms 37 and 38. Upon oscillation of the arm 17, the bracket 15 simultaneously moves the positioning pin 13 into contact with a container 12 which is immediately adjacent the cutting position. At the instant that the pin 13 engages the container, the conveyor is moving to the right and consequently the engaged container is moved to the left relative to its bucket 5, thereby positioning the container against the rear upstanding edge of said bucket in proper relation thereto to receive the subsequently cut slip. The knife 32 is reciprocated through the medium of a bell crank of which the lever 17 comprises one arm and a lever 39 which comprises the other arm, as shown in Fig. 7. This bell crank is pivoted to the machine frame at 40 and its arm 39 extends downwardly and is pivotally connected, as at 41, to a link 42 which is connected at its opposite end to a crank pin 43 and held on the pin by a collar 44. The pin is rotated by an eccentric crank 45 which therefore applies an operating force to the levers 39 and 17, which in turn control the operation of the knife 32.

As the buckets carrying the containers 12 are

moved along by the conveyor 4, they will arrive at predetermined positions B, C, and D immediately below a plurality of chute members 46, Figs. 1 and 2. The chute members 46, Figs. 11-15, are disposed immediately above and in alignment with the conveyor buckets, Fig. 1. These chute members 46 are not limited to any particular number, but a separate chute member is provided for each individual row of tablets to be fed into the container, and there are 10 a number of slideways, four being shown in each of the chute members 46, Fig. 11. In the present instance there is shown three chute members for feeding three individual rows of four tablets.

Immediately above the chute members are a plurality of members spaced to provide channels 47, Figs. 1, 2 and 37, in an inclined conveyor 48. These channels permit the tablets to slide or roll downwardly and be fed from a hopper 49 into the chute members 46. The channels of the inclined conveyor 48 are so disposed that four of the channels 47 lie in perfect alignment with the slideways in each of the chute members. This arrangement is to allow one tablet at a time to be fed from each channel to a respective chute member, and since there are four channels for each chute member four tablets are fed to each chute member to provide a row of four tablets, Figs. 11 to 15.

At the lower end of the inclined conveyor 48 and disposed immediately above the channels 47 are a pair of escapement bars 50 and 51, Figs. 1, 2 and 37, which extend transversely across the channels 47 of the conveyor 48. These escapement bars are for the purpose of limiting the number of tablets being fed from the channels into the chute members. The bars 50 and 51, Figs. 2 to 6, carry a plurality of pairs of sprung-urged pins 52, each pair of pins extending through the bars 50 and 51 and in alignment with each channel 47, Fig. 2. The number of pairs of pins in the bars are equal to the number of channels 47 and are for the purpose of limiting or stopping the tablets being fed.

The bars 50 and 51 have a plurality of recesses 53 each of which receives a spring 54 surrounding a pin 52, Figs. 5 and 6. The front escapement bar 51, Figs. 1 and 37, is connected to a crank arm 55 by bolts 56. The crank arm 55 is pivoted around the shaft 57 and has extending beyond the pivot an extension 58 which has a threaded aperture 59 adapted to receive a bolt 60, Fig. 37. The bolt 60 has threaded thereon a pair of nuts 61 which contact the extension 58 for securing the adjustment of the bolt. The bolt 60 on the crank arm 55 contacts the underside of a bar 62, which is integrally connected to a second crank arm 63, integral with a bearing 64 pivoted about the shaft 65. The shaft 65 may be carried by the frame in any convenient manner. A crank arm 66, Fig. 37, extends from the bearing 64 and has a cam roller mounted at 67 which cooperates with a cam 68. The back escapement bar 50 is integrally connected to a crank arm 69 which is pivoted at 70. The crank arm 69, Fig. 37, has a threaded recess 72 adapted to receive a threaded bolt 73 which contacts the extension arm 62 to limit the downward movement of the escapement bar 50. This bolt 73 is adjustable to predetermine the movement of bar 50.

The tablets 11, Fig. 37, roll down the inclined conveyor 48 in the channels 47 on their peripheral edges and come in contact with the sprung-urged pins 52 which are disposed in the back bar 50, and are stopped thereby. Each pin is spring-

urged to prevent injury to the tablets when the pin moves into clamping contact with a tablet 71.

Upon the rotation of the cam 68 to reciprocate the arm 63 vertically upward, the crank arm 69 and the escapement bar 50 are lifted by the bar 62 from the position shown in Fig. 37 to move the pins 52 carried by this bar out of contact with the tablets. Simultaneously with the lifting of the crank arm 69 by the extension 62, the crank arm 55 is released for downward movement around its pivot 57 to bring the pins on the escapement bar 51 into position in front of the tablets, as shown in Fig. 3. The escapement bar 50, therefore, allows only one tablet at a time 10 to be fed from each channel to the escapement bar 51. The further rotation of the cam 68 moves the arm 66 about its pivot to oscillate the arm 63 and bar 62 downwardly, so that this bar contacts the bolt 60 of the arm 55 and causes the arm 20 55 to pivot about the shaft 51. This downward movement of the extension 62 raises the arm 55 and its cooperating escapement bar 51 from the position shown in Fig. 3 to the position shown in Fig. 4 to release the tablets. Simultaneously 30 with the raising of the bar 51, the escapement bar 50 moves downwardly to the position shown in Figs. 4 and 37, whereby each pin 52 of this bar contacts a second tablet in each line of tablets and prevents further feeding movement of 30 these and the succeeding tablets. The escapement bar 51 therefore in turn allows only a single tablet 71 of each channel to be fed into a tablet-rotating bar 74, Figs. 1, 20, 21 and 37.

The tablet-rotating bar 74, Figs. 1, 20-22 and 35 37, is disposed immediately below the escapement bar 51 and adjacent the lower end of the inclined conveyor. This bar 74 has a bar 75 which is provided with a plurality of recesses 76, these recesses being equal in number to the number of channels 47. The bar 74, Figs. 1 and 37, is connected at one end by a link 77 to a pivot stud 78. At the other end it is connected to a bell crank lever, Fig. 1, having arms 79 and 80. The arm 80 is pivoted at 81 to a link 82 for connection to its actuating mechanism (not shown).

The vertical reciprocation of the link 82 oscillates the bell crank which reciprocates the bar 74 and brings the recesses 76 into and out of alignment with the channels 47, as shown in Figs. 20 to 22. Fig. 20 shows the bar 74 at the extreme right-hand position of its stroke and just starting to move to the left. In this position a tablet 71, fed past the escapement bar 51, falls partially into a recess 76. The continued movement of the bar 74 turns the tablet over to the position shown in Fig. 21 and then to the position shown in Fig. 22, in which latter position it is exactly perpendicular to its former position in channels 47. In the reciprocation of the bar 74 reciprocating tablet agitators 83 and 84, Figs. 20 to 22, 32 and 33, assist in the re-positioning of the tablets 71. The reciprocating tablet agitators 83 and 84 will be hereinafter described.

At the extreme left-hand position of the bar 74, the tablets 71, having been re-positioned, will be allowed to drop into the respective channels 85 of the chute members 46, Fig. 11, the channels 85 being in alignment with the recesses 76 and the channels 47. Each chute member 46 has four of these channels 85 which are separated by the guides 86, Fig. 11. In position B, Figs. 1 and 2, the first four channels 47 of the inclined conveyor feed the first chute member 46, in position C the second four channels feed the second chute member 46, while in position D the

last four channels feed the third chute member.

Each of the separate channels 85 in the individual chute members 46 has a vertically extending finger 87, Figs. 17 and 18. The fingers 87 associated with each chute member 46 are pivoted on a stud or shaft 88, and have, above their lower ends 89, a perpendicular extension 90, Figs. 11, 17 and 18. The purpose of this extension 90 is to control the feed of the tablets 71 from the channels 85 so that all four tablets 10 will be fed simultaneously into the container 12. The finger 87, Fig. 17, has a pendulum movement about the stud 88 and is controlled by a bar 91 mounted on pusher rods which will be hereinafter described.

The chute members 46 are bolted by bolts 92 to the vertical face 93 of an angular bracket 94, Figs. 17, 18 and 34, the horizontally extending arm of which is integrally connected with a boss 95 adjustably secured to an actuating rod 96.

Tablet pusher bars 97, Figs. 2, 17, 18, 34 and 35, which are positioned between the chute members 46, as best shown in Fig. 2, are mounted on a pusher shaft 98. The bracket 94 carries a shaft or stud 99 to which a downwardly extending link 100 is pivoted. The opposite end of the link 100 is pivoted to a shaft 101, Figs. 17, 18 and 35, carried by the bar 91. The shafts 98, which carry the pushers 97, extend through the bar 91 and are rigidly secured thereto as shown in Fig. 35. This bar 91, which is positioned immediately behind the chute member 46 and below the bracket 94 extends transversely of all three chute members 46 and cooperates with springs 102, Figs. 17 and 18, mounted in said 35 chute member for controlling the movement of the fingers 87. The movements of these fingers control the feed of tablets 71 into the container 12 as previously stated.

The pusher bar shafts 98, Figs. 17 and 18, for 40 the pusher bars 97, have at their rear ends bearings 103 positioned on the shafts 98 by collars 104 and 112, the collars 104 being fastened to the shafts and the collars 112 being loose thereon. The bearings 103 have downwardly extending levers 105 attached thereto, as indicated at 45 106. At its lower end each lever 105 is integrally connected with a boss portion 107 fastened to a shaft 108. Also fastened to the shaft is a lever 109, carrying a roller 110 which contacts a cam 111. This cam 111, upon rotation, moves the roller 110, which, through levers 109 and 105, causes reciprocation of the pusher bar shafts 98. A helical spring 113, mounted between a rear collar 104, Fig. 17, fastened to 50 each shaft 98 and the collar 112, acts as a safety spring to permit the bearing 103 to move idly relative to its shaft 98 if the pusher 97 in the rearward movement encounters any undue resistance.

The chute-actuating rod 96, Figs. 17 and 18, extends vertically downward from the boss 95 and is fastened at its lower end to a boss 114, Fig. 17, which carries a horizontal arm 115. At the end of the arm 115 is a boss 116 which is adapted to receive a rod or link 117. The rod 117 is positioned against displacement in the boss 116 by the collars 118 and 119. The rod or link 117 extends vertically upward and in parallel alignment with the rod 96 and has at 65 its upper end a yoke 120, pivoted at 121 to an arm 122 of a bell crank pivoted at 124. The other arm 123 of the bell crank carries a cam roller 125 which cooperates with a driving cam (not shown). The rotation of the cam moves 70 75

the roller 125 and causes the bell crank lever to pivot about its pivot 124, to vertically reciprocate the link 117 and the rod 96.

The path along which the pusher bars 97 are moved by the shafts 98 and the rod 96 is diagrammatically shown in Fig. 41. The upward reciprocation of the rod 96 takes place during the forward movement of the shafts 98 and consequently the pusher bars move diagonally upwardly and forwardly, as shown in Fig. 17, during the vertical upward movement of the chute members 46. Each chute member in its upper position receives in its channels 85 a set of four tablets fed from the recesses 76 of the tabletting bar 74. The tablets which have been fed into the channels 85 are held therein by the extensions 90 on the pivoted fingers 87. In this position of the extensions 90, the pusher arm 97 is at the front of a chute member 46 and the bar 91 pressing against the fingers 87 retains them in their forward position against the action of the springs 102.

During the major portion of the downward movement of the rod 96 the shaft 98 is inoperative and consequently the chute members 46 and pusher bars 97 move vertically downward as a unit until the rod 96 approaches the end of its travel when the shaft 98 begins to move rearwardly. Rearward movement of the shaft 98 causes the bar 91 to move away from the chute members to thereby release the springs 102. The springs 102 move the fingers 87 backwardly and allow four tablets to fall from each chute member into the front of a container 12 positioned at the points B, C and D in Figs. 1 and 2. The feeding positions of the tablet in the front of the container are shown in Figs. 12, 13 and 14, Fig. 12 showing the first row of tablets in initial position in the container; Fig. 13 showing the second row of tablets in initial position and the first row of tablets in adjusted position; and Fig. 14 showing the third row of tablets in fed position and the first and second rows of tablets in adjusted position.

As shown more particularly in Fig. 2, the pusher bars 97 overlie the buckets positioned between the chute members. Consequently these bars, when the rod 96 has completed its downward movement, engage the first and second rows of tablets which initially are fed to the same relative position in the container as shown in Figs. 12, 12a, 13 and 13a. The rod 96 having completed its downward movement, the shaft 98 continues to move rearwardly and causes the pusher bars 97, engaged with the first and second rows of tablets, to move the same toward the rear of the container, as shown in dotted lines in Figs. 12a and 13b, thereby properly positioning the tablets in these rows and these rows in the containers.

This movement having been completed, the shafts 98 and pusher bars 97 are then moved forwardly to clear the tablets and having cleared the same the rod 96 again moves upwardly while the shaft 98 moves forwardly, thereby returning the chute member and pusher bars to their positions shown in Fig. 17 and setting the fingers 87 for reception and retention of tablets in said chute member.

As shown in Fig. 14, the third row of tablets is initially fed into its proper position adjacent the front edge of the container. Therefore a pusher bar 97 is not provided for this row of tablets. However, it may happen that individual tablets in this third row may become tilted in

being fed from the chute member 46 at position D. Accordingly there may be provided means operated by this chute member for kicking any such tilted tablets forwardly of the container so that they will lie properly in a flat position in said container. As shown in Figs. 1 and 40, an operating pin 220, secured to the side of the chute member 46 at position D, is adapted to engage a lever 221 secured to a stud 222 pivoted in a bracket 223 fastened in any convenient manner to the machine frame. At its end opposite the lever 221 the stud 222 carries a kicker arm or plate 224 which is positioned to overlie the third row of tablets and at its outer end engage any tablets which may be tilted in the container.

A container in which a third row of tablets has been fed from the chute member 46 moves during the upward movement of the chute member into a position beneath the kicker arm or plate 224; consequently upon the downward movement of the chute member 46 to place a third row of tablets in the next following container the lever 221 will be rotated counterclockwise by the pin 220, thereby causing the kicker arm or plate to swing across the third row of tablets and kick any tilted tablets into their proper position lying flat within the container. A spring 225, interposed between the bracket 223 and a depending lug or extension 226 of the arm 221, urges said arm into engagement with the pin 220 and maintains the kicker arm above the upper surface of the tablets in the container.

The conveyor 4 successively moves the containers 12, with their slips 22 and tablets 71, to position E, Figs. 1 and 2, where a slip 126, containing printed matter or instructions, is placed in superposed position on the tablets 71 in each container 12. The slip 126 is fed from a hopper 127 by suction means (not shown). The hopper 127, Figs. 1, 2 and 19, is disposed vertically and immediately adjacent the conveyor.

A slip 126 from the bottom of the hopper 127 is deposited upon a guide table 128, Fig. 19, mounted on a bracket 129 by means of bolts 130. The guide table 128 has recesses 131, Fig. 19, to assist in feeding the slip 126 over the table 128. A plate 132 bolted to the front face of the hopper 127 has a forwardly and downwardly inclined portion overlying the bucket 5 and container 12 at position E (Figs. 1 and 2) for the purpose of guiding the slip 126 into its proper position in the container. Working in conjunction with the guide table 128 is a pusher arm 133, Fig. 19, having a perpendicular arm 134 extending across the table 128. This pusher arm 133 is pivoted at 135 to the arm 136 of a bell crank lever pivoted at 138. The arm 137 of the bell crank lever is pivoted at 139 to a link 140 which in turn is pivoted at its other end to a crank pin 141 carried by a crank member 142 fixed to a shaft 143. The crank pin 141 and link 140 oscillate the bell crank lever and cause the pusher arm 133 to reciprocate horizontally across the guide table 128, thereby pushing the slip 126 into the container 12 at position E. The container 12, with the slip 22, the tablets or articles 71, and the top slip 126, is clearly shown in Figs. 28 and 29.

The subsequent movement of the conveyor 4 brings each container 12 to a position F, Figs. 1 and 2, to receive a folded printed circular 144, Figs. 1, 2 and 30.

The unit for folding the printed circular is immediately adjacent the conveyor at the posi-

tion F, Figs. 1 and 2, and consists of a horizontal folding blade 145, Fig. 1, attached to an arm 146 which is actuated back and forth by means not shown. The folding blade 145 contacts the printed circular 144, being fed through and by the feed rolls 147 and 148, mounted on the shafts 149 and 150 which are journaled on the frame in any conventional manner. The printed circular or paper is fed downward through guides 151 into guides 152, where it is engaged by the first folding blade 145 and then fed to the feed rolls 153 and 154. The feed rolls 153 and 154 are mounted on shafts 155 and 156, and feed the folded circular into the upwardly inclined guides 157.

A second folding blade 158, Fig. 1, between feed rolls 153, 154 and guides 157, is carried by an actuating arm 159 and is reciprocated vertically to fold the circular a second time and to feed the same into vertically disposed guides 160 which are bracketed to the frame at 161. The circular 144 is then contacted by a third folding blade or member 162 to refold the twice folded circular. The folding member 162 is horizontally disposed and is reciprocated to fold and feed the circular into horizontally disposed guide members 163. The guide members 163 have an opening or recess 164 which allows a fourth folding member 165 to contact the circular 144 to again fold and feed it downwardly to a position where it is engaged by the fifth folding member 166 (Figs. 2 and 25 to 27). The fifth folding member or arm is horizontally disposed and carried by the actuating arm 167, Fig. 25.

This fifth folding member is reciprocated horizontally to fold the circular 144 and feed it through the spring-urged guide member 168 and the guide 169, Figs. 25 and 26. The guide member 168 has a fixed upper portion 170, to which is secured at one end a helical spring 171 for constantly urging the guide member 168 into a predetermined position spaced from the lower guide 169. This urging action assists the folding arm 166 in creasing the circular when feeding it into the containers 12. The lower guide 168 is bracketed to the back magazine wall bracket 172 by bolts 173. The back bracket may be attached to the frame bracket 8 in any conventional manner. The circular 144, which has been folded five times, conforms in substantial dimensional size to that of the container 12, so that it can be easily and readily inserted therein. The completely folded circular 144 is pushed by the fifth folding member 166 into the container 12.

The lid 175 of each container 12 as it approaches the position F is engaged by the guide member 176, Figs. 1, 2 and 23 to 26. This guide member 176 is disposed vertically adjacent the conveyor 4 and is attached to the angle bracket 8 in any convenient manner. The member 176 has an integral arm 177 extending horizontally above the conveyor buckets 5, Figs. 25 and 26. This arm 177 has an angle or cam portion 178 to move the lid toward closed position (see Fig. 2). The extension arm 177 may be integrally attached to the vertical arm 176, or it may be hinged in any convenient manner (not shown). The lid 175 of the container, as the container is fed along, comes in contact with the angled portion 178 of the guide to progressively close the lid, Figs. 23 to 26.

The extreme end of the guide arm 177, opposite the angled end 178, substantially overlies the lid 175 of the container 12, but the lid 175 is

prevented from completely closing by the horizontal arm 174 which extends into a position beneath a corner of the lid of the container at the position F (Fig. 25). The lid is prevented from closing so that the folded circular 144 can be fed from the guide members into and inserted in the container 12 as shown in Fig. 26.

The next movement of the conveyor causes each container to be moved away from position F and from the extension arm 174. The right end of the guide arm 177 pushes the lid 175 downward into a substantially closed position, as shown in Fig. 31. In this latter position the conveyor moves the containers under a presser roll 180, Figs. 1, 2 and 27, which is rotatably mounted on a stud shaft 181. The presser roll presses the lid 175 into closed position to complete the packaging operation. The closed packages are then conveyed away to a table 182 for shipping, and the like.

The hopper 49, Fig. 37, is mounted on an angular frame bracket 185, which is attached to the bracket 8. The top portion of the bracket 185 supports the hopper 49, the tablet-agitator bars 83 and 84, and tablet rails 186 to form the inclined conveyor 48. This inclined conveyor consists of a plurality of feed channels 47, hereinbefore described.

The tablet rails 186 are connected at the rear and front of the hopper to transverse bars 187 and 189 which are bolted to the frame bracket 185 in any suitable manner as by bolts 188, shown at the right of Fig. 37. Each rail 186 has pins 189 at opposite ends thereof, and these pins are adapted to fit into recesses 190 in the bars 187 and 189. The rails 186 fit into recesses 191 which are disposed perpendicular to the recesses 190, Figs. 38 and 39.

The inclined conveyor 48 has a plurality of tablet-agitator bars 83 and 84, disposed between 40 and above the tablet rails 186, Figs. 32 and 33, there being a pair of agitator bars for each channel 47. These tablet agitators 83 and 84 are supported at the back of the conveyor by the bar 187 and supporting bars 194 and 195, and at the 45 front by a support bar 196, Fig. 36, and by a bar not shown. The support bar 194 for the bar 84, at the rear of the inclined conveyor, has integral therewith at both ends a shaft 197. The agitating bars 83, which cooperate with the agitating bars 84, are carried in a similar manner by a support bar 195, having shaft extensions 198 at both ends. These support bars and shafts are parallel and adjacent to each other and extend through an aperture 194 in the hopper 49, Fig. 37. 55

At the upper end of the conveyor, the support 194, carried by the shaft 197, is interconnected with arms 199. These arms 199, one at each end of the support 194, are rigidly mounted on a shaft 201 journaled at both ends in the hopper 60 support bracket 185. Mounted on the front end of the shaft 201, Fig. 37, is a lever 203 connected at 204 to a link 205. The link 205 is rotatably fastened to a crank 206 driven by means not shown. Rotation of the crank 206 therefore imparts a reciprocating movement to the agitator bars 84. The shaft extensions 198 are rotatably mounted in levers 207 rigidly mounted on the shaft 209. Fastened to the back end of shaft 209 (Fig. 37) is a lever 210 connected at 211 to a link 212. The link 212 is rotatably fastened to a crank 213 driven by means not shown. Rotation of the crank 213 imparts a reciprocating movement to the bars 83. The connecting mechanisms for actuating the agitator bars 83 and 84 are similar 75

in every detail. The link 205 and its actuating mechanism for the bars 83 is disposed on one side of the hopper, while the link 212 and its actuating mechanism for the bars 84 is disposed on the opposite side of the hopper. The supporting bar 196 at the lower end of the conveyor 48 has a shaft portion 214 at each end, which is adapted to be received in connecting levers 215 for supporting the agitator bars. The levers 215 have openings 216 adapted to receive the shaft portions 214 providing a movable support, swinging in an arc, and allowing the reciprocation of the agitating bars 83. The support levers 215 at their opposite ends are supported by the shaft 51 carried by the frame 185 for supporting the bar 196 which carries the tablet agitator bar 83. A similar mechanism mounted on the shaft 70 supports the tablet agitator 84.

The bars 83 and 84 are reciprocated so that on the forward stroke of one bar the other is moving backwards. This is obvious, since the bars 83 and 84 feed the tablets down the tablet rails 186 into a position to be received by the tablet-rotating bar 74, Fig. 22. The bars 83 in their forward position, in conjunction with the bars 84 at their backward position, cooperate with the bar 74 in turning the tablets around in position to be fed into the chute members. The reciprocation of the bars 83 and 84 have the further purpose of agitating and feeding the tablets along the channels 47 of the inclined conveyor 48.

It is to be understood that the packaging machine hereinbefore described has its various actuating mechanisms connected to a main drive shaft (not shown) for synchronizing the series of operations in timed relationship.

Operation

The open containers 12 are placed in conveyor buckets 5 and properly positioned therein by the pin 13 just prior to reaching the position A, Fig. 1, where a slip of paper 22 is fed and cut off and finally inserted in the bottom of the container by the presser arms 34, 37 and 38. The containers are then moved in succession by the intermittently operating conveyor to the position B, under the first chute member 46, where each container receives the first row of tablets 71, coming from the inclined conveyor 48 past the escape-50 ment bars 50 and 51, to be turned around by the rotating bar 74 and allowed to fall into the chute member 46.

The pusher bar 97 positions the row of tablets to the back of the container at the next position, after which it is fed along to position C. At this position it receives a second row of tablets by repeating the same cycle of operation, and in its next position the second pusher bar 97 properly positions the second row of tablets along 60 the median line of the container. The conveying of the container with the two rows of tablets to the position D allows it to receive a third row of tablets from the chute member at this point. If the kicker arm 224 (Figs. 1 and 40) is employed, the next position of the container will be below this arm, which is thereupon operated to cause the tablets of the third row to lie flat in the container.

When a container is moved to position D to 70 receive the last row of tablets, the conveyor has positioned additional containers at positions C and B and A to receive the second and first row of tablets and the bottom paper or slip 22, respectively. After each container is filled it is 75 then conveyed to position E, Fig. 1, to receive a

top slip 126 (Figs. 1, 19 and 29) fed from the hopper 127. The slip is pushed by a reciprocating arm 133 into each container 12 into superposing relationship with the tablets 71.

Each container 12 is next conveyed to the position F, where a printed circular 144 which has been folded five times by the folding unit is inserted into the container. The lid 175 of each container 12, while approaching the position F, contacts the angular guide member 177 which 10 functions to move the lid 175 toward a closed position, but the lid is prevented from closing completely by an extension arm 174 so that the folded circular may be inserted.

After the folded circular is inserted, the container is conveyed past the guide member 177 under a presser roll 180 which applies pressure upon the partially closed container lid to snap the lid 175 into complete closed position to form a completed package.

It will be seen that after the containers 12 have been placed in the buckets 5 the packaging machine automatically performs its series of operations to provide a container with its full contents, and then completely closes the container to 25 form a completed package, this automatic operation being accomplished without any manual means whatsoever.

Claims to the tablet conveyor and to the circular folding and loading mechanism and associated container closing devices are not presented in this application, claims to such devices being presented in divisional applications.

Changes may be made in the form, construction and arrangement of the parts without departing from the spirit of the invention or sacrificing any of its advantages, and the right is hereby reserved to make all such changes as fairly fall within the scope of the following claims.

What is claimed as new and desired to be secured by Letters Patent of the United States is as follows:

1. In a packaging mechanism, in combination a conveyor for feeding open containers along a predetermined path, means arranged in the path of the conveyor for feeding a slip into the container, means for feeding an exact number of tablets in the container, and means operatively connected to the tablet-feeding means for shifting the tablets relative to said slip to reposition the tablets into predetermined positions in the container.

2. In combination, a conveyor for moving containers along a predetermined path, means adjacent said conveyor for feeding a web of paper, means for cutting slips of paper from the web and inserting the slips in said containers, means for actuating the cutting means, means on said actuating means in advance of said cutting means for shifting the containers into predetermined positions on said conveyor during movement of the containers to said slip inserting means, and means on said actuating means but beyond said cutting means for shifting a tilted slip into proper position in the container.

3. In a feeding mechanism for tablets to be packaged comprising a plurality of guide chutes, means for reciprocating the chutes to receive the tablets, pivoted means in the chutes for holding the tablets to prevent their discharge from said chutes, means adjacent the chutes for positioning the tablets in a container being fed under the chutes, said positioning means having an oscil-

latory movement and actuating the holding means.

4. A packaging machine for packaging a plurality of articles into an open container having a hinged closure, comprising means for feeding the container to a predetermined position, means for moving a slip to a predetermined position, means for inserting the slip in the bottom of the container, means for causing the container to be further advanced to another predetermined position after the slip has been inserted therein, means for depositing an article in a preliminary position in the container and on the slip, and means for thereafter shifting the article relative to the slip to permanent position in the container.

5. A packaging machine for packaging a plurality of articles into an open container having a hinged closure, comprising means for feeding the container to a predetermined position, means for moving a slip to a predetermined position, means for inserting the slip in the bottom of the container, means for causing the container to be further advanced to another predetermined position after the slip has been inserted therein, means for depositing an article in the container and on the slip, means for shifting the article relative to the slip to permanent position in the container, means for causing the container to be further advanced to another predetermined position, means for feeding another article in the container, and means for shifting the second article relative to the slip and the first article to permanent position in the container adjacent the first article.

6. A packaging machine for packaging a plurality of articles into an open container having a hinged closure, comprising means for feeding the container to a predetermined position, means for moving a slip to a predetermined position, means for inserting the slip in the bottom of the container, means for causing the container to be further advanced to another predetermined position after the slip has been inserted therein, means for depositing an article in the container and on the slip, means for shifting the article relative to the slip to permanent position in the container, means for causing the container to be further advanced to another predetermined position, means for feeding another article in the container, means for shifting the second article relative to the slip and the first article to permanent position in the container adjacent the first article, means for causing the container to be moved to another predetermined position, means for depositing another article in a predetermined position in said container, and means for shifting any tilted article into proper position in the container.

7. In a tablet packaging machine, means for successively conveying containers to be filled to a plurality of spaced filling stations, means at each of said stations for depositing a tablet in the container at said station, and means between certain of said stations for shifting the tablet deposited in the container, at the preceding station, relative to said container and into a predetermined position therein.

8. In a tablet packaging machine, means for successively conveying containers to be filled to a plurality of spaced filling stations, means at each of said stations for depositing a tablet in the container at that station and remote from an edge thereof, means between the first and second 75 of said plurality of stations for shifting the

tablet into juxtaposition to said edge of the container, and means beyond said second station for shifting the tablet deposited in the container at the second station into juxtaposition to the tablet deposited in the container at the first station.

9. In a tablet packaging machine, means for successively conveying containers to be filled to a plurality of spaced filling stations, means at the first of said stations for depositing a tablet in said container, and remote from an edge thereof, means between the first and second of said stations for shifting said tablet into juxtaposition to said edge of the container, means at the second station for depositing a tablet in said container remote from the tablet deposited in the container at the first station, and means beyond the second station for shifting the tablet deposited in the container at the second station into juxtaposition to the tablet deposited in the container at the first station.

10. In a tablet packaging machine, means for successively conveying containers to be filled to a plurality of spaced filling stations, means at each of said stations for depositing a tablet in the container at said station, means between certain of said stations for shifting the tablet deposited in the container, at the preceding station, relative to said container and into a predetermined position therein, and means beyond the last of said plurality of stations for shifting any tilted tablets in the container into a flat position therein.

11. In a tablet packaging machine, means for successively conveying containers to be filled to a plurality of spaced filling stations, means at the first of said stations for depositing a tablet in said container, and remote from an edge thereof, means between the first and second of said stations for shifting said tablet into juxtaposition to said edge of the container, means at the second station for depositing a tablet in said container remote from the tablet deposited in the container at the first station, means beyond the second station for shifting the tablet deposited in the container at the second station into juxtaposition to the tablet deposited in the container at the first station, and means beyond said last mentioned means for shifting any tilted tablets in the container into a flat position therein.

12. In a tablet packaging machine, means for successively conveying containers to be filled to a plurality of spaced filling stations, means at the first of said stations for depositing a tablet in said container, and remote from an edge thereof, means between the first and second of said stations for shifting said tablet into juxtaposition to said edge of the container, means at the second station for depositing a tablet in said container remote from the tablet deposited in the container at the first station, means beyond the second station for shifting the tablet deposited in the container at the second station into juxtaposition to the tablet deposited in the container at the first station, and means at the last of said plurality of stations for depositing a tablet in a predetermined final position in said container.

13. In a tablet packaging machine, means for successively conveying containers to be filled to a plurality of spaced filling stations, means at the first of said stations for depositing a tablet in said container, and remote from an edge thereof, means between the first and second of said

- stations for shifting said tablet into juxtaposition to said edge of the container, means at the second station for depositing a tablet in said container remote from the tablet deposited in the container
- 5 at the first station, means beyond the second station for shifting the tablet deposited in the container at the second station into juxtaposition to the tablet deposited in the container at the first station, means at the last of said plurality
- 10 of stations for depositing a tablet in a predetermined final position in said container, and means beyond said last station for shifting any tilted tablet deposited in the container at said station into a flat position therein.
- 15 14. In a tablet packaging machine, means for successively conveying containers to be filled to a plurality of spaced filling stations, means at each of said stations for depositing a row of tablets in said container, and means between certain of said stations for simultaneously shifting all of the tablets of a row of tablets deposited in the container at the preceding station into a predetermined aligned position in the container.
- 20 15. In a tablet packaging machine, means for successively conveying containers to be filled to a plurality of spaced filling stations, means at the first of said stations for depositing a row of tablets in said container remote from an edge thereof, means between the first and second of
- 25 said stations for simultaneously shifting all of the tablets of the row of tablets deposited in the container at the first station into a predetermined aligned position in juxtaposition to said edge of the container, means at a second of said plurality
- 30 of stations for depositing a second row of tablets in said container and remote from the row of tablets deposited therein at said first station, and means beyond the second station for simultaneously shifting all of the tablets of the row deposited at the second station into a predetermined aligned position in juxtaposition to the first
- 35 row of tablets.
- 40 16. In a tablet packaging machine, means for successively conveying containers to be filled to a predetermined filling station, a receptacle at said station and having a chute for receiving a tablet to be deposited in the container therat, holding means extending into said chute for preventing discharge of said tablet from said chute,
- 45 means for operating said holding means to release said tablet for discharge into the container, means for shifting the deposited tablet to a predetermined position in said container, and means operably connected to said tablet shifting means
- 50 for controlling the operation of said releasing means.
- 55 17. In a tablet packaging machine, means for successively conveying containers to be filled to a predetermined filling station, a tablet supply source relatively remote from said conveying means, a shiftable receptacle at said station and having a chute for receiving a tablet from said supply source when the receptacle is in a position remote from the container on the conveying
- 60 means and for depositing the tablet in said container when in a position in juxtaposition thereto, means for shifting said receptacle between said positions, holding means extending into said chute for preventing discharge of the tablet from
- 65 said chute, means for operating said holding means to release the tablet for discharge into the container, and means operative in timed relation
- 70 to the operation of said receptacle shifting means for operating said releasing means when the receptacle is in juxtaposition to the container.
- 75 18. In a tablet packaging machine, means for successively conveying containers to be filled to a predetermined filling station, a table supply source relatively remote from said conveying means, a shiftable receptacle at said station and having a chute for receiving a tablet from said supply source when in a position remote from said conveying means and for depositing the tablet in said container when in a position in juxtaposition thereto, a reciprocating member upon which said receptacle is mounted for shifting between said positions, means for driving said reciprocating member, a tablet positioning bar reciprocable transversely to the path of movement of said reciprocating member for shifting the deposited tablet to a predetermined position in said container, and means for driving said tablet positioning bar in timed relation to the operation of said reciprocating member.
- 80 19. In a tablet packaging machine, means for successively conveying containers to be filled to a predetermined filling station, a tablet supply source relatively remote from said conveying means, a shiftable receptacle at said station and having a chute for receiving a tablet from said supply source when in a position remote from said conveying means and for depositing the tablet in said container when in a position in juxtaposition thereto, a reciprocating member upon which said receptacle is mounted for shifting between said positions, means for driving said reciprocating member, a tablet positioning bar carried by said reciprocating member and reciprocable relatively thereto along a path transverse to the movement of said reciprocating member for shifting the deposited tablet to a predetermined position in said container, and means for driving said tablet positioning bar in timed relation to the operation of said reciprocating member.
- 85 20. In a packaging machine, a conveyor having a succession of bucket-like sections for receiving in each section a container to be filled, means at a predetermined station along said conveyor for depositing articles to be packaged in said containers, means positioned along said conveyor in advance of said station for shifting each container, during movement of the conveyor, into a predetermined position in its bucket-like section, means for depositing a slip into the container thus positioned, means for shifting a tilted slip to cause it to lie flat in said container, means for supporting said container shifting means, said slip depositing means and said slip shifting means for simultaneous movement toward and from said container, and means for operating said supporting means.
- 90 21. A method for packaging tablets in containers which comprises successively conveying containers to be filled to a plurality of spaced filling stations, depositing at each of said stations a row of tablets in said container, before said containers reach a succeeding station shifting all of the tablets of a row of tablets deposited in the container at the preceding station into a predetermined aligned position in the container.

CERTIFICATE OF CORRECTION.

Patent No. 2,227,378.

December 31, 1940.

MICHAEL J. MILMOE, ET AL.

It is hereby certified that error appears in the printed specification of the above numbered patent requiring correction as follows: Page 9, second column, line 6, claim 18, for the word "table" read --tablet--; and that the said Letters Patent should be read with this correction therein that the same may conform to the record of the case in the Patent Office.

Signed and sealed this 18th day of February, A. D. 1941.

(Seal)

Henry Van Arsdale,
Acting Commissioner of Patents.
